SHOE SOLE OR SIMILAR ARTICLE

Maurice C. Smith III, Bristol, R.I., assignor to Marbill Company, Providence, R.I., a corporation of Rhode Island

Filed Aug. 20, 1964, Ser. No. 81,369

Term of patent 14 years

(Cl. D7—5)

FIG. 1 is a plan view of a shoe sole or similar article showing my new design;

FIG. 2 is a longitudinal-sectional elevation of line 2—2 of FIG. 1; and

FIG. 3 is an elevational view taken from the right of FIG. 1.

I claim:

The ornamental design for a shoe sole or similar article, substantially as shown.
